UNITED STATES PATENT OFFICE

VINCENT LINK, OF DETROIT, MICHIGAN.

MOTOR VALVE MECHANISM.

1,100,023.

Specification of Letters Patent. Patented June 16, 1914.

Application filed July 12, 1913. Serial No. 778,683.

To all whom it may concern:

Be it known that I, VINCENT LINK, a citizen of the United States of America, residing at Detroit, in the county of Wayne and State of Michigan, have invented certain new and useful Improvements in Motor Valve Mechanism, of which the following is a specification, reference being had therein to the accompanying drawings.

- 10 In removing the cylinders of explosive engines from the base for the purpose of cleaning, refitting or the like, it is necessary in the usual construction to also remove the connections between the valves and the valve driving shaft. Where tappet rods are used in combination with a cam shaft it involves considerable trouble as it is difficult to re-adjust the tappet rods and cams in proper relation.
- 20 This invention relates to explosive engines wherein the valve driving mechanism is mounted to form a unit with the cylinders that is bodily removable from the base without altering the adjustment of the valve mechanism or in any way disturbing any portions of it except the connection between the main or crank shaft and the cam shaft.

The invention consists in the matters hereinafter set forth and more particularly 30 pointed out in the appended claims.

In the drawings, Figure 1 is a view, partially in elevation and partially broken away and in section, of a motor that embodies features of the invention; and Fig. 2 is a view, 35 partially in side elevation and partially in section, of an end portion of the motor showing one form of connection between the crank and cam shafts.

As herein indicated a base 1 and crank 40 case 2 house a crank shaft indicated at 3 that is operatively connected in the usual manner to pistons (not shown) plying in cylinders 4. The latter are cast *en bloc*, or are secured or mounted together so as to 45 constitute a unit structure that can be taken away from the base without difficulty. Each cylinder is provided with a puppet valve closure 5 that is disposed in the usual manner to seal an annular valve seat 6 formed 50 in a passage way indicated at 7 which extends through the cylinder wall and water jacket with an outlet through a face 8

against which an intake or exhaust manifold may be clamped. The design and arrangement of the valve closure and seat with the 55 passage which it controls may be as desired as the valve structure itself does not form a part of this invention. As herein shown the valve is easily accessible for inspection or withdrawal through an opening that is 60 closed by a cap 9.

An elongated bushing 10 or guide sleeve is mounted in the casing of the cylinder in axial alinement with the valve seat 6 and closure 5. A depending tubular stem 11 on 65 the closure is reciprocable longitudinally in the sleeve. A shoe 12 is secured in the lower end portion of the stem 11 in such manner as to be adjustable longitudinally relative to the stem. This may be conveniently accomplished by the use of a screwthreaded stud 13 on the foot engaging similar interior threads in the sleeve. An annular stop 14 formed on the foot holds a spring member in compression between it and the wall of the 75 cylinder through which the bushing 10 extends, the latter acting as a keeper for the spring. The stop is cut away to form apertures through which cotter pins 16 may be inserted to hold the stem and stud 13 in ad- 80 justed position.

A valve gear casing 17 that is formed integrally on the cylinders 4 or is secured thereto, houses a cam shaft 18 that is journaled therein in suitable relation to the shaft 85 3. Cams 19 on the shaft bear against the shoes 12 of the cylinder valves to oscillate the latter and thereby operate the valves in the usual manner. The casing is closed by a cover plate 20 which is removably secured as by studs 21 and nuts 22 or the like over the valve stems and their connections to completely house the latter. The opening that is normally sealed by the cover 20, is so disposed that the lower portion of 95 the casing 17 forms an oil well of such depth that the cam shaft and shoes may be made to run in oil or other lubricant, at all times. The cam shaft is driven in timed relation to the main shaft 3 by suitable 100 means as for example, gear trains indicated at 24, sprocket chain connections, or other suitable means. This connecting mechanism may be housed by a removable

casing 25, as indicated in Fig. 2, which permits inspection and disconnection of the parts.

When it is necessary to inspect the interiors of the cylinders of the motor, this is readily accomplished by simply removing the cylinders with the cam shaft and valve connections housed in the casing that forms a part of the cylinders, bodily from the engine base. Thus the cylinders may be cleaned or adjusted and returned to place without any disturbance of the valve operating mechanism. The alignment of the valve mechanism is not disturbed and the arrangement also provides for adequate lubrication of the parts. As the valve mechanism is completely housed, it is practically noiseless, the lubricant aiding in muffling any sound from the coating parts.

Obviously, changes in the details of my invention may be made without departing from the spirit of my invention and I do not care to limit myself to any particular form or arrangement of parts.

What I claim is:—

1. In a motor, an engine base, a main shaft in the base, cylinders on the base, valve mechanism mounted on the cylinders, a valve casing on the cylinders housing the mechanism, and operating connections between the mechanism and shaft, the cylinders, valve mechanism and casing forming a structural unit bodily removable from the base.

2. In a motor, an engine base, a main shaft therein, cylinders on the base, valves in the operating mechanism therefor mounted on the cylinders, a casing on the cylinders housing the valve and mechanism and detachable means connecting the mechanism and shaft, the cylinders, casing, valves and valve mechanism housed by the casing constituting a structural unit bodily removable from the base.

3. In a motor, an engine base, a main shaft therein, cylinders on the base, puppet valves mounted on the cylinders, mechanism mounted on the cylinders for operating the puppet valves, and a casing mounted on the cylinders for housing the puppet valves and operating mechanism, the casing and inclosed parts forming a structural unit with the cylinders that is bodily removable from the base.

4. In a motor, an engine base, cylinders on the base, a casing secured on the cylinders and adapted to form a receptacle for lubricants, a valve operating mechanism for the cylinders mounted in and housed by the casing, the cylinders, casing and inclosed mechanism forming a structural unit bodily removable from the engine base.

5. In a motor, an engine base, cylinders mounted thereon, a puppet valve for each

cylinder controlling a seat in the lateral extension thereof, stems extending from the puppet valves, a casing on the cylinders housing the stems, and a cam shaft mounted in the casing for reciprocating the stems, the cylinders, casing, valves and cam shaft forming a structural unit bodily removable from the engine base.

6. In a motor, an engine base, a cylinder mounted thereon, a casing on the side of the cylinder, a cam shaft journaled in the casing, a puppet valve for the cylinder, and a stem on the valve reciprocated by the cam shaft, the valve and the operating connections therefor together with the casing and cylinder forming a structural unit independent of the base.

7. In a motor, an engine base, cylinders secured together and mounted on the base, a casing formed on the side of the cylinders, valves for the cylinders, a valve operating mechanism housed by the casing, the connected cylinders and casing together with the valves and inclosed valve operating mechanism constituting a structural unit independent of the base.

8. In a motor, an engine base, cylinders mounted thereon provided with annular valve seats, puppet valve closures for the seats, stems on the closures, and bushings secured on the cylinders in which the stems are reciprocable, a casing secured on the cylinders, and a cam shaft rotatable in the casing for reciprocating the stems, the casing and inclosed shaft and stems forming with the cylinders and valves a structural unit bodily removable from the base.

9. In a motor, an engine base, cylinders mounted thereon, a casing secured on the sides of the cylinders, puppet valves for the cylinders having stems extending into the casing, shoes adjustably secured on the stems, and a cam shaft journaled in the casing and adapted to bear against and reciprocate the shoes, the casing forming a lubricant well and the cylinders, casing and inclosed valve mechanism constituting a structural unit bodily removable from the base.

10. In a motor, an engine base, cylinders thereon, a casing secured on the sides of the cylinders, guide bushings secured in the cylinders, puppet valves in the cylinders having guide stems extending into the casing through the bushings, a cam shaft journaled in the casing for reciprocating the stems and springs for projecting the stems against the cam shaft, the casing, cylinders, valves and mechanism inclosed in the casing constituting a structural unit bodily removable from the base.

11. In a motor, integrally united cylinders, a casing formed on the side of the cylinders, valves for the cylinders, and valve

operating mechanism housed by the casing, the cylinders and casing together with the valves and inclosed valve operating mechanism constituting a structural unit.

5 12. In a motor, integrally connected cylinders, a puppet valve for each cylinder, a cam shaft operatively connected to the valves, and a casing on the cylinders housing the valves and the connected cam shaft,

the cylinders, casing, valves and cam shaft 10 forming a structural unit.

In testimony whereof I affix my signature in presence of two witnesses.

VINCENT LINK.
